Primary Examiner — Karen Kearney

Assistant Examiner — Debra Callahan

(74) *Attorney, Agent, or Firm* — Dentons US LLP

(57) **CLAIM**

The ornamental design for an electronic device impact screen with graphical user interface, as shown and described.

DESCRIPTION

FIG. 1 is a front view of a first embodiment of an Electronic device impact screen with graphical user interface showing the new design; and,

FIG. 2 is a front view of a second embodiment of an Electronic device impact screen with graphical user interface showing the new design.

The broken lines represent the display screen, text, and portions of the graphical user interface and form no part of the claimed design.

1 Claim, 2 Drawing Sheets
